(57) **CLAIM**

The ornamental design for a motor vehicle, toy and/or replica, as shown and described.

DESCRIPTION

FIG. 1 is a right, front perspective view of a motor vehicle, toy and/or replica, wherein the convertible top of the motor vehicle is depicted in a deployed position;

FIG. 2 is a right, rear perspective view of the motor vehicle, toy and/or replica of FIG. 1;

FIG. 3 is a front elevation view of the motor vehicle, toy and/or replica of FIG. 1;

FIG. 4 is a rear elevation view of the motor vehicle, toy and/or replica of FIG. 1;

FIG. 5 is a left side elevation view of the motor vehicle, toy and/or replica of FIG. 1;

FIG. 6 is a right side elevation view of the motor vehicle, toy and/or replica of FIG. 1;

FIG. 7 is a top plan view of the motor vehicle, toy and/or replica of FIG. 1;

FIG. 8 is a right, front perspective view of the motor vehicle, toy and/or replica of FIG. 1, wherein the convertible top of the motor vehicle is depicted in a retracted position;

FIG. 9 is a right, rear perspective view of the motor vehicle, toy and/or replica of FIG. 8;

FIG. 10 is a front elevation view of the motor vehicle, toy and/or replica of FIG. 8;

FIG. 11 is a rear elevation view of the motor vehicle, toy and/or replica of FIG. 8;

FIG. 12 is a left side elevation view of the motor vehicle, toy and/or replica of FIG. 8;

FIG. 13 is a right side elevation view of the motor vehicle, toy and/or replica of FIG. 8; and,

FIG. 14 is a top plan view of the motor vehicle, toy and/or replica of FIG. 8.

The broken lines are for illustration purposes only and form no part of the claimed design.
